STRINGED MUSICAL INSTRUMENT

John B. Cousineau, Forest Park, Ill.

Application December 23, 1949, Serial No. 134,803

7 Claims. (Cl. 84—312)

1

This invention relates to stringed musical instruments, especially to instruments of the type of the electric steel guitar, and more particularly to an improved tuning mechanism for such instruments.

The utility of the conventional steel guitar, and other similar stringed instruments used with electrical amplification, is seriously limited by the fact that the strings must be adjusted to a fixed chord tuning which cannot be changed to any appreciable extent while the instrument is being played. Thus, with such an instrument there is no satisfactory means of playing chords or partial chords other than those corresponding to the initial fixed tuning of the strings. Obviously, the resultant lack of flexibility and musical range greatly restricts the popularity and adaptability of such instruments especially for use in orchestras and other musical groups.

Various tuning devices and tuning changers have been suggested for use with instruments of the foregoing character in order to permit relatively rapid changes in the string tuning. However, such of these devices as have been capable of meeting musical and playing requirements have not been altogether satisfactory both for the reason that they have been unduly complicated in structure and operation and also because they are often inaccurate and unreliable in execution of the required changes in tuning. For example, most of the prior art devices employ string-tensioning levers or rollers which are attached to the ends of the playing strings, the opposite ends of the strings being anchored to the instrument whereby the string tension may be varied by exerting a greater or lesser pull on the strings longitudinally thereof. Such devices have been found to be unreliable because the levers or rollers which are attached to the ends of the strings tend to wear or become misadjusted with the result that they do not always return to their original positions and thus the initial fixed tuning of the strings is disturbed. In addition, most of the prior art string-tensioning devices do not afford sufficient flexibility with respect to the number of chord changes that can be executed, and those devices that do permit a substantial number of chord changes are unduly complex in construction and operation.

Accordingly, a primary object of my invention is to provide, in a stringed musical instrument of the above-mentioned type, novel means for readily effecting frequent and rapid changes in the tuning of the strings.

Another object of the invention is to provide,

2

in a stringed musical instrument of the character described, a tuning mechanism for selectively altering the tension of the strings or predetermined groups thereof which is capable of accurate adjustment and which, even with repeated use, does not tend to disturb the original fixed tuning of the strings.

A further object of the invention is to provide, in a stringed musical instrument of the character described, a novel tuning mechanism having cooperating means for increasing or decreasing the tension of predetermined combinations of strings.

An additional object of the invention is to provide, in a stringed musical instrument of the character described, a novel pedal-operated tuning mechanism for increasing or decreasing the tension of predetermined combinations of strings by deflecting or relaxing the strings intermediate the anchored ends thereof.

Still another object of my invention is to provide, in a stringed instrument of the character described, means for selectively varying the tension of the strings whereby a wide variety of chord changes may be effected.

Other objects and advantages of the invention will become apparent upon reference to the subsequent detailed description and the accompanying drawings, in which:

30 Fig. 1 is a perspective view of an electric steel guitar provided with a tuning changer or string-tensioning device comprising one specific embodiment of my invention;

35 Fig. 2 is an enlarged fragmentary plan view of the tuning changer at the right-hand end of the instrument as viewed in Fig. 1;

Fig. 3 is a transverse sectional view through the tuning changer taken along the line 3—3 of Fig. 2;

40 Fig. 4 is a longitudinal sectional view through the tuning changer taken along the line 4—4 of Fig. 2 and showing parts of the tuning changer in a position effecting a change from the initial fixed tuning;

45 Fig. 5 is a fragmentary sectional view taken along the line 5—5 of Fig. 2 and showing the manner in which an operating element of the device effects a different change from the initial fixed tuning; and

50 Fig. 6 is a fragmentary elevational view of one element of the device as viewed substantially along the line 6—6 of Fig. 5.

Broadly speaking, my tuning changer unit comprises a combination of relatively independent but commonly operated mechanical means for

increasing or decreasing the tension of selected combinations of playing strings. As mentioned above, I have found that it is not satisfactory to control string tension by anchoring the strings at one end and varying the longitudinal pull at the other ends of the strings. Accordingly, in my device string tension is increased by the action of string-deflecting elements engaging the strings transversely intermediate their opposite ends which are anchored securely in the body of the instrument, and string tension is decreased by relaxing the strings upon rocking movement of pivotally mounted string supports which engage the strings intermediate the anchored ends thereof. My invention also comprises a common operating mechanism, preferably including a pedal bank, for simultaneously increasing or decreasing the tension of selected combinations of strings. Thus, each playing string has three possible pitches corresponding to the normal or initial tension, increased tension, or decreased tension, and by selecting various combinations of these possible conditions of tension for each string it will be seen that numerous variations of the tuning pattern are made possible.

Referring first to Fig. 1 of the drawings, the invention is illustrated by an electric steel guitar comprising a wood or plastic body 11 which is provided on its upper surface with a fingerboard 12 extending longitudinally thereof in the conventional manner. A plurality of playing strings, eight being shown in the present case as indicated at 13, 14, 15, 16, 17, 18, 19, and 20, are tensioned along the body of the instrument extending over a nut 21 at one end of the fingerboard 12 and are connected to a plurality of conventional tuning keys 22. The playing strings are anchored at their opposite ends in a tuning changer unit, indicated generally at 23, which is mounted adjacent the opposite end of the body 11. The unit 23 comprises a principal feature of the present invention and will be described hereinafter in greater detail.

The body 11 is supported on a pair of tubular legs 24 having laterally extending base portions 26. The tuning changer unit 23 is operated by means of a pedal bank comprising a plurality of telescoping rock shafts 28, one for each pedal, extending between the base portions 26. Each of the shafts 28 has secured adjacent one end thereof a rocker arm 29, and a pair of actuating cables 31 extend upwardly from opposite ends of the rocker arm 29 to certain movable portions of the tuning changer unit 23, as hereinafter described.

The instrument selected for illustration being an electric steel guitar, there is shown in Fig. 1 an electrical pickup device 32 of any well known type which is mounted below the playing strings 13 to 20 and is adapted to transmit the sound vibrations of the strings to an amplifier and loud speaker unit associated with the instrument. The pickup device 32 is provided with suitable volume and tone control means (not shown) which are inserted in the pickup circuit for modifying the volume and tone of the string vibrations. These controls are adapted to be operated manually by means of a pair of control knobs 33 and 34 which are disposed at one side of the instrument and are readily accessible to the hand of the player.

Pursuant to the objects of the present invention, tuning changer or string-tensioning means is provided for selectively varying at will the pitch of predetermined groups of the playing strings 13 to 20. Such variation in pitch is accomplished

by means of the string-tensioning unit 23 which functions independently of the tuning keys 22 and independently of any other string-tensioning mechanism with which an instrument of this type may be equipped.

Referring now to Figs. 2 to 6, the tuning changer or string-tensioning mechanism 23 comprises a substantially rectangular framework or base structure, indicated generally at 36, which is rigidly mounted in an opening 37 in the body 11. The base 36 is provided with a pair of spaced upright parallel sides 38 having a roller shaft 39 extending transversely therebetween at the innermost end of the base 36 with a plurality of grooved string rollers 41, one for each playing string, rotatably mounted on the shaft 39. An anchor bar 42 (Fig. 2), for purposes hereinafter described, is secured between the sides 38 adjacent the rollers 41 by means of a pair of screws 43. An end wall or cross member 44 connects the sides 38 at the outer edge of the base 36 and is provided with a plurality of upright bores 46 having tapered or outwardly flared upper and lower openings, as indicated at 47 (Fig. 4). The playing strings 13 to 20 are retained at one end of the instrument by the tuning keys 22 from which they extend along the fingerboard 12 and over the rollers 41, under the anchor bar 42, through the operating portions of the tuning changer mechanism in an inclined direction as hereinafter described, and finally downwardly into the bores 46 in the end wall 44 where they are firmly anchored by means of suitable enlarged portions or retainers, such as indicated at 48, affixed to the opposite ends of the strings.

For deflecting the playing strings 13 to 20 in order to increase the tension thereof, a plurality of depressible bars 49 are supported in parallel side-by-side relation extending transversely across the playing strings between the sides 38 of the base 36. Each of the bars 49 is provided with a series of transverse slots 51 spaced longitudinally of the bar corresponding to the spacing of the playing strings 13 to 20 and extending downwardly into the bar from the upper edge thereof, the slots 51 in each bar 49 being aligned with the corresponding slots in the other bars whereby to provide continuous transverse passageways through which the playing strings 13 to 20 extend. Extending downwardly to the bottom of each of the slots 51 is a threaded bore 52 (Fig. 4) for receiving a string-deflecting element in the form of an adjustable screw 53 adapted to extend to any desired extent into the bore 52 for engaging at its inner end the corresponding playing string upon downward movement of the bar 49. Each of the screws 53 has an enlarged head portion 54 provided with a socket adapted to receive a suitable wrench or tool for effecting rotary adjustment of the screw. A helical spring 56 encircles each of the screws 53 and bears at its opposite ends against the head portion 54 and the top of the bar 49 for stabilizing and retaining the screws 53 in desired adjusted position within the bores 52. It will be understood that not all of the bores 52 in the bars 49 are fitted with screws 53 but instead the number and distribution of the screws 53 are selected to obtain the desired number and type of chord changes. Thus, as seen in Fig. 2, the device herein illustrated has one bar 49 with no screws 53, four bars with one screw 53 each, one bar with two screws 53, and two bars with three screws 53 each.

For actuating the bars 49, an elongated recip-

roating member in the form of a stem or plunger 57 (Figs. 3 and 4) depends centrally from each bar, the plungers 57 being slidably received in a plurality of bores 58 formed in an inclined bed member 59 secured between the side portions 38 of the base structure 36. The lower ends of the plungers 57 extend below the bed 59 and each plunger has fastened thereto a separate operating cable 31. The pedals 27 being tiltable in opposite directions and each rocker arm 29 having two cables secured thereto, it will be seen that only four pedals are needed to operate eight of the bars 49. Each of the bars 49 is provided with a pair of compression springs 61 (Fig. 3) engaging the bar at its lower face on opposite sides of the plunger 57 and being received in a pair of cavities or recesses 62 on the upper face of the bed 59. As a result of the action of the springs 61, the bars 49 are normally urged upwardly into elevated or non-deflecting position, upward movement of each of the plungers 57 being limited by means of a cross pin 63 extending diametrically through the plunger 57 below the bore 58 for engaging the underside of the bed 59. Any desired combination of the bars 49 may be depressed downwardly by rocking the appropriate pedals 27 to effect downward movement of the corresponding cables 31 attached to the lower ends of the plungers 57. Downward movement of the bars 49 is limited by means of stop members in the form of a pair of spaced rails 64 (Fig. 3) integral with the bed 59 and extending longitudinally thereof. A pair of spaced pins 66 project upwardly adjacent each end of the bed 59 on opposite sides of the group of bars 49 for loosely retaining the latter in side-by-side relation and for preventing twisting or turning movement of the bars 49 as a result of rotation of the plungers 57 in the bores 58.

It will be seen that upon suitable manipulation of the pedals 27, selected combinations of the bars 49 may be depressed in order to effect engagement of the screws 53 mounted thereon with any desired group of playing strings 13 to 20, the playing strings thereby being deflected downwardly for increasing the string tension. For example, as seen in Fig. 4, the third bar 49 from the left is shown in depressed condition and the playing string 20 is being deflected downwardly by the screw 53 mounted in the bar. In like manner, the string 20 can also be deflected by depression of the right hand bar 49 or the third bar from the right as seen in Fig. 4. The bed 59 is disposed within the base structure 36 at an angular or inclined relationship therewith and substantially parallel to the normal position of the playing strings extending thereabove (Fig. 4) so that the plungers 57 and the screws 53 are substantially perpendicular to the playing strings. Thus, the screws 53 always engage the playing strings substantially perpendicularly whereby to effect uniform deflection upon repeated manipulation of the pedals 27 and whereby to avoid any tendency toward slippage of the ends of the screws 53 along the playing strings.

For relaxing the playing strings 13 to 20 in order to decrease the tension thereof, the tuning changer is provided with a plurality of pivotally mounted string supports each comprising an upright block or lever 67 (Figs. 4-6) pivotally or rockably supported on a shaft 68 extending between the sides 38 adjacent the outermost end of the base 36. A grooved roller 69 is rotatably mounted on a shaft 71 in a recess or notched portion 72 (Fig. 6) at the top of each of the levers

5 67. A projection in the form of a retaining pin 73 extends from the bottom of each of the levers 67 and has secured thereto one end of a tension spring 74 with the other end of the spring 74 being fastened to a cross pin 75 (Fig. 3) extending transversely between the sides 38 and held in place by a pair of pins 76 projecting downwardly from the bed 59. Thus, the tension springs 74 acting upon the lower end of each of the levers 67 normally retain the levers in upright position with the bottom portion of the levers in abutment against the outer end edge of the bed 59, as seen most clearly at 77 in Fig. 4.

10 15 In the normal undeflected position of the playing strings 13 to 20, each string extends over its roller 41 and thence inclines downwardly through the aligned slots 51 in the bars 49 and passes over the roller 69 on the corresponding lever 67 and downwardly to its anchored position in the end wall 44. As hereinafter explained, the levers 67 are so arranged that under the normal tension 20 of the playing strings, the levers are retained in an upright position.

25 20 For each of the playing strings 13 to 20 there is provided an auxiliary string, designated for convenience by the reference numerals 13a to 20a, the auxiliary strings extending generally parallel to the playing strings and in alternating relationship therewith (Fig. 2). The outer end of 30 each of the auxiliary strings 13a to 20a extends through a bore (not shown) in the upper end of one of the levers 67 and is anchored by means of a retainer 78. The opposite end of each of the auxiliary strings 13a to 20a is firmly retained in a suitable aperture (not shown) in the anchor bar 42 by means of a screw 79. The bars 49 are provided with a plurality of aligned slots 51a, similar to the slots 51, through which the auxiliary strings 13a to 20a extend in the same manner as the playing strings 13 to 20. The slots 51a are likewise provided with threaded bores 52a, similar to the bores 52 in the slots 51, for receiving a plurality of deflecting screws 53a having head portions 54a and stabilizing springs 56a (Fig. 3). Upon depression of the appropriate bars 49, it will be understood that selected auxiliary strings are engaged substantially perpendicularly by the string-deflecting screws 53a whereupon the corresponding levers 67 are pivoted or rocked about the shaft 68 against the action of the springs 74 and the associated string-supporting rollers 69 are swung inwardly of the instrument whereby to relax the corresponding playing strings and decrease the tension thereof. As in the case of the screws 53, the screws 53a are also distributed in the bores 52a according to any predetermined pattern for obtaining the desired combination of possible chord changes.

60 65 In order to permit the use of a plurality of string deflecting screws 53 and 53a in adjacent positions in any one of the bars 49 without interference between the head portions 54 and 54a, the threaded bores 52 and 52a are staggered in each bar 49 to provide two parallel rows extending longitudinally of the bar (Fig. 2). Thus, the row of threaded bores 52 receives the screws 53 for deflecting the playing strings 13 to 20 and the other row of threaded bores 52a receives the screws 53a for deflecting the auxiliary strings 13a to 20a.

70 75 Referring now to Fig. 5, one of the levers 67 is shown in solid lines in its normal upright position as retained by the spring 74 with the playing string 20 extending downwardly over the roller 69 to its anchored position in the bore 48 in the

end wall 44. Upon downward deflection of the auxiliary string 20a, the lever 67 is rocked to the position shown in broken lines in Fig. 5 with the result that the playing string 20 is relaxed slightly by the inward movement of its supporting roller 69.

It is an important feature of my invention that the axis of the roller 69 is positioned above the axis of the pivot shaft 68 and to one side thereof in the direction of the end of the playing string or the outermost end of the tuning changer unit. As a result of this horizontal displacement of the respective axes and the angular relationship of the string extending over the roller 69, as shown in Fig. 5, the resultant or net force of the component tensions existing in the portions of the string 20 on either side of the roller 69 falls substantially along or closely adjacent to the center line, indicated at 81, connecting the axes of the roller 69 and the pivot shaft 68. The net effect of this arrangement is that in the normal upright position of the lever 67 there is no appreciable force or torque due to the tension of the playing string, tending to effect pivotal movement of the lever inwardly to string-relaxing position, or else the force is so slight that the spring 74 is sufficient to counteract this torque and retain the lever 67 in upright position.

By correlating the relative angles of the playing string with respect to the center line 81 and the extent of lateral displacement or spacing between the axes of the roller 69 and the pivot shaft 68 to produce this balanced condition, it will be seen that only slight tension need be exerted by the spring 74 to retain the lever 67 in normal upright position. If the pivotal mounting of the lever 67 with respect to the location of the roller 69 and the angular position of the playing string passing over the roller 69 were such that a substantial torque existed tending to rotate the lever to string-relaxing position, it will be seen that a relatively strong spring 74 would be required to insure normal upright positioning of the lever 67. If a relatively strong spring 74 were required, it follows that a greater depressing force by the bars 49 and the screws 53a and, consequently, stronger foot pressure on the pedals 27 would be necessary to effect deflection of the auxiliary strings 13a to 20a thereby seriously diminishing the ease and rapidity of operation of the device.

In Fig. 4, the string 20 is shown in deflected position under increased tension. Because of the above described balanced condition of the lever 67, the increased tension in the string 20 and the resultant decrease in the angle of the long portion of the string to the left of the roller 69, as viewed in Fig. 4, cause the resultant force due to the string tension on opposite sides of the roller to swing counterclockwise toward or beyond the center line 81 connecting the axes of the roller 69 and the pivot shaft 68. Thus, direct downward deflection of the playing string 20 does not result in pivotal movement of the lever 67, but, on the contrary, urges the lever even more strongly to its normal upright position with the lower portion thereof in contact, as at 77, with the edge of the bed 59.

Thus, my invention provides for altering the tension of any of the playing strings 13 to 20 by exerting a localized transverse downward pressure on the same intermediate their anchored or rigidly held ends whereby to increase the tension of the strings without rocking the pivotally mounted string-supporting rollers 69. Simi-

larly, the tension of any one of the playing strings 13 to 20 may be decreased by exerting a downward deflecting pressure on its associated auxiliary strings 13a to 20a whereby to swing the string-supporting roller 69 to a position where the playing string is relaxed and its tension is decreased. Thus, the initial tension of each playing string, as determined by the tuning keys 22, may be either increased or decreased by relatively independent means. By avoiding any change in the positions of the fixed ends of the playing strings during operation of the tuning changer mechanism, there is no tendency for the initial fixed tuning of the strings to be disturbed. When the bars 49 are restored to normal elevated position after depression thereof, the tensions of the associated playing strings are uniformly restored to their initial values.

It will be understood that numerous combinations of tuning patterns may be obtained by means of the tuning changer comprising my invention. For example, by varying the number, distribution, and threaded adjustment of the screws 53 and 53a, different combinations or predetermined groups of playing strings may be subjected to increased or decreased tension corresponding to the depression of one or more of the bars 49 by manipulation of the pedals 27. Thus, the nature of my string-tensioning mechanism is such that a wide range of flexibility in tuning pattern may be achieved dependent upon the distribution and adjustment of the deflecting screws for both the playing strings and the auxiliary strings.

Although the invention has been described in connection with one particular embodiment thereof, it will be understood that various modifications and equivalent structures may be resorted to without departing from the scope of the invention as defined in the appended claims.

I claim:

1. In a stringed musical instrument having a plurality of playing strings tensioned thereon, means for selectively varying the pitch of said playing strings comprising a plurality of upright levers pivotally mounted adjacent one end of the instrument and having portions of the playing strings tensioned thereover, a plurality of auxiliary strings operatively connected to said levers for effecting pivotal movement of the latter, a bed member disposed below said strings and having a plurality of bores therein, a plurality of depressible bars extending transversely across the strings and carrying a plurality of adjustable string-deflecting elements adapted to engage and deflect downwardly a predetermined combination of said playing and auxiliary strings, each of said bars having a depending plunger disposed for reciprocal movement in one of said bores, spring means coacting between said bed and said bars for normally urging the latter to elevated non-deflecting position, and operating means including cables secured to the lower ends of said plungers for depressing said bars.

2. In a stringed musical instrument having a plurality of playing strings tensioned thereon, means for selectively varying the pitch of said playing strings comprising string-relaxing means operatively associated with each of said playing strings for decreasing the tension thereof, a plurality of auxiliary strings extending generally parallel to said playing strings and operatively connected to said string-relaxing means, and a common actuating means extending transversely across said playing and auxiliary strings for en-

gaging and deflecting predetermined combinations thereof.

3. In a stringed musical instrument having a plurality of playing strings tensioned thereon, means for selectively varying the pitch of said playing strings comprising string-relaxing means operatively associated with each of said playing strings for decreasing the tension thereof, a plurality of auxiliary strings extending generally parallel to said playing strings and operatively connected to said string-relaxing means, a plurality of depressible bars extending transversely across said playing and auxiliary strings and carrying a plurality of string-deflecting elements for engaging and deflecting predetermined combinations of said playing and auxiliary strings, and operating means for depressing said bars whereby to vary the tension of said predetermined combinations of playing and auxiliary strings.

4. In a stringed musical instrument having a plurality of playing strings tensioned thereon, means for selectively varying the pitch of said playing strings comprising a plurality of levers pivotally mounted adjacent one end of the instrument and having portions of the playing strings tensioned thereover, the tension of said playing strings being alterable by pivotal movement of said levers, spring means normally retaining said levers in a position corresponding to the initial fixed tension of the playing strings, a plurality of actuating strings attached to said levers and deflectable for effecting pivotal movement of the levers to alter the tension of said playing strings, and means for deflecting a predetermined combination of said actuating strings.

5. In a stringed musical instrument having a plurality of playing strings tensioned thereon, means for selectively varying the pitch of said playing strings comprising a plurality of upright levers pivotally mounted intermediate their ends, portions of the playing strings being tensioned over the upper portions of said levers, a plurality of springs coacting with the lower ends of said levers and tending to hold said levers against pivotal movement whereby to maintain the playing strings under normal tension, a plurality of auxiliary strings each operatively connected to one of said levers adjacent its upper end for effecting pivotal movement of the levers against the action of said springs upon deflection of the auxiliary strings whereby to decrease the tension of the playing strings extending thereover, and operating means comprising a plurality of string-deflecting elements adapted to engage and deflect predetermined combinations of said auxiliary strings.

6. In a stringed musical instrument having a

plurality of playing strings tensioned thereon, means for selectively varying the pitch of said playing strings comprising a supporting structure mounted adjacent one end of the instrument, a plurality of levers pivotally mounted within said structure with portions of the playing strings tensioned thereover, a cross bar mounted on said structure in spaced relation from said levers, a plurality of auxiliary strings extending parallel to said playing strings each being attached at one end to the upper portion of one of said levers, and anchored at its opposite end to said cross bar, a plurality of adjustable string-deflecting elements disposed above said strings for engaging and deflecting the same, the tension of said playing strings being increased upon direct deflection thereof by said elements and being decreased upon deflection of the auxiliary strings associated therewith, and operating means associated with said string-deflecting elements for deflecting predetermined combinations of said playing and auxiliary strings.

7. In a stringed musical instrument having a plurality of playing strings tensioned thereon, means for selectively varying the pitch of said playing strings comprising a plurality of upright pivotally mounted levers having rollers mounted adjacent the upper ends thereof above the pivot points of said levers with portions of the playing strings being tensioned over said rollers and extending downwardly to anchored position adjacent one end of the instrument, spring means coacting with said levers for normally retaining said levers in substantially upright position, a plurality of auxiliary strings for said levers each being affixed at one end to the upper portion of its associated lever for effecting inward pivotal movement of said rollers, a plurality of adjustable string-deflecting elements for engaging and deflecting predetermined combinations of playing and auxiliary strings, the pivot point of each of said levers being spaced slightly from its roller inwardly of the instrument, whereby downward deflection of said playing strings inwardly of said levers tends to hold said levers against pivotal movement.
